United States Patent Office

Des. 185,604
Patented June 30, 1959

185,604

PULL

Wallace T. Johnson, Burbank, Calif., assignor to Amerock
Corporation, Rockford, Ill., a corporation of Illinois

Application May 28, 1956, Serial No. 41,681

Term of patent 14 years

(Cl. D50—3)

Fig. 1 is a front view of a pull showing my new design.
Fig. 2 is a sectional view taken along the line 2—2 of
Fig. 1.

The design is characterized by the particular figure representation shown on the concave face of the knob.

I claim:

The ornamental design for a pull, substantially as
shown and described.
